UNITED STATES PATENT OFFICE.

JAMES J. MURPHY, OF NEW HAVEN, CONNECTICUT.

AUTOMATIC VALVE.

Application filed September 11, 1924. Serial No. 737,131.

The present invention relates to automatically operating valves useful particularly with the radiators of steam heating systems. The purpose of such valves is to 5 permit the automatic expulsion of air from the radiators under action of internal pressure generated by the expanding vapors and further to allow the valves to close automatically to prevent re-admission of air, 10 whereby a partial vacuum or pressure below atmospheric can be maintained so as to gain the best working condition in the heating system. Another purpose of valves of this kind is to effect sealing against the leakage 15 of water when the radiator is flooded and to permit automatic siphoning of water from the valve when the water level in the radiator or piping falls below said valve. The objects of the invention, among 20 others, are to produce an efficient valve composed of the minimum number of parts so as to facilitate and cheapen production, and at the same time produce a valve which will perform all the required functions.

25 The invention will be described herein-after with reference to the accompanying drawings wherein—

Figure 1 is a vertical sectional view taken 30 through the central portion of the improved valve;

Figure 2 is a side elevation of the improved valve; and

Figure 3 is a detail sectional view showing 35 in perspective a part of the crown of the valve.

Describing the embodiment of the invention illustrated by said drawings, the cylindrical or other suitably shaped shell 1 forms the casing of the valve, and this shell is open 40 at the top with a double flange around the open end to provide a seat 2 and an over-hanging flange 3, respectively to receive and retain a diaphragm 4 and a rotatable cover or cap 5. A hollow float 6 is contained 45 within the casing 1 and the bottom of said float is hermetically closed by a flexible diaphragm 7, which rests on an upwardly extending depression 8, at the bottom of the casing so as to elevate said float from the 50 bottom of the casing. This float is arranged to move up and down when the valve is operating and to keep and guide this float, the inwardly depressed circumferential beading 9, is formed in the shell. This beading is 55 flattened or broken at points to allow the passage of air or vapor around the float.

A nipple 10, having a threaded end, is secured at the bottom of the casing and this nipple provides means for connecting the valve to a radiator. A siphon tube 11, passing through said nipple, is secured to the casing by expanding the end 12, and which end, being the inlet end, it will be noted, is located below the bottom of the float 6 so that the latter will not interfere with the 60 draining of water through said siphon.

The valve element 13 is carried by the float 6 and said element has a conical or pointed tip which fits in the valve seat 14 of the valve body 15. The latter body is supported 70 by the diaphragm 4 and the upper end is housed within the crown 16 of the cover 5. An auxiliary valve element consisting of the disk 17 is adapted to close the upper or outer port of the vent passage 21 in the 75 valve body and the pin valve element closes the lower or inner port of said vent passage.

The said disk valve element 17 is contained wholly within the said crown and has ears 18 which engage elongated bosses 19 80 in the sides of said crown. By this means, the disk 17 is allowed an independent vertical movement to open or close the vent 21 and when the cover is rotated, for the purpose of grinding the valve seat, the said 85 disk will turn with the rotating cover. Dust or other matter that may accumulate within the crown will be expelled by air escaping through holes 20 located diametrically opposite in the sides of the crown 16.

90 Describing the operation of the improved valve it will first be pointed out, in order to get the very best results from a steam heating system, a working condition should be established and maintained wherein the internal pressure is below the atmospheric pressure, or in other words, a partial vacuum should be created within the system. The valve hereinbefore described permits such desirable conditions to be established 95 and maintained for immediately upon raising steam within the system, the accumulated air is expelled through the open vent, in the valve body. When the external pressure is slightly greater than the internal 100 pressure, the upper diaphragm moves into the lower flexed position the auxiliary or check valve 17 operating to close the outer port of the vent against admission of air. The float which carries and operates the 110 main valve closing element is of a known type containing a highly volatile liquid which

expands under action of the heated steam so that the lower diaphragm at the bottom of said float is moved to the lower flexed position thereby lifting the float and valve element to close the lower port in the vent or air outlet in the valve body. It will be noted that the chamber containing the float and located below the upper diaphragm, is doubly sealed against the admission of air 10 therein from the outside and when the pressure within said chamber falls below atmospheric pressure, the change in pressure will cause the flexing of the upper diaphragm from its upper or normal flexed position to the lower flexed position and thus tending to act conjunctively with the lower diaphragm in effecting the tight closure of the valve so that a partial vacuum or low pressure condition may be maintained within 15 said chamber.

It will be understood the float is of the ordinary type and operates in a known manner, when the valve casing is flooded, to close the air vent in the valve body to stop escape 20 of water. Also the siphon is of a known type and operates in a known manner to carry off water which may be present in the valve chamber.

I claim:

30 1. A valve of the class described having a casing, a pair of flexible diaphragms located one above the other within said casing and arranged to operate separately or conjunctively to maintain an internal low pressure working condition within the valve 35 chamber below the upper diaphragm, a valve body member supported by said upper diaphragm, a valve element co-operatively associated with the lower diaphragm, 40 said valve body having a vent therethrough arranged to be closed and opened by means

of said valve element respectively operated by the upwardly and downwardly flexing of the lower diaphragm, an independently operating auxiliary valve element operating to open and close said vent, a cap arranged to cover and rotate on said casing, a housing for said auxiliary valve element carried by said cap, and engaging means between said auxiliary element and said housing whereby said auxiliary element is caused to rotate with said housing.

2. A valve of the class described having a casing, automatically operative valve members and means for operating the same contained within said casing, said members consisting of a valve body member and a floating member carrying a valve element, an upper and a lower diaphragm within said casing, said upper diaphragm carrying 60 said body member and the lower diaphragm being carried by said floating member, said upper diaphragm hermetically sealing the valve chamber within said casing, said diaphragms being operative separately or conjunctively to maintain an internal low pressure working condition in said chamber, an auxiliary valve element contained within a rotatable housing for sealing the vent in the valve body against admission of air into 70 said valve chamber, an elevated seat for said floating member, a nipple leading from the lower end of said casing, a siphon within said nipple having its inlet below said diaphragm, and an inwardly depressed circumferential beading around said casing providing a guide for said floating member.

Signed at New Haven, county of New Haven, State of Connecticut, this 6th day of September, A. D. 1924.

JAMES J. MURPHY.
